UNITED STATES PATENT OFFICE.

CHARLES E. GROVES, OF ATTICA, OHIO.

WORK-BENCH FOR SALOONS.

SPECIFICATION forming part of Letters Patent No. 511,048, dated December 19, 1893.

Application filed April 12, 1893. Serial No. 470,081. (No model.)

To all whom it may concern:

Be it known that I, CHARLES E. GROVES, a citizen of the United States, residing at Attica, in the county of Seneca and State of Ohio, have invented a new and useful Work-Bench for Saloons, of which the following is a specification.

My invention relates to a work bench and sink for saloons, and the objects in view are to provide a simple and convenient device of the class having all the necessary appointments arranged in convenient positions, and to provide such a construction that the members composing it may be removed or separated for the purpose of cleaning, repairing, &c.

Further objects and advantages of my invention will appear in the following description, and the novel features thereof will be particularly pointed out in the appended claims.

In the drawings: Figure 1 is a perspective view of a device embodying my invention. Fig. 2 is a longitudinal sectional view of the same, upon the line 2—2 of Fig. 1. Fig. 3 is a transverse sectional view upon the line 3—3 of Fig. 2. Fig. 4 is a detail view, in perspective, of the drip-pan. Fig. 5 is a similar view of the bottle-rack, or false cover of the bottle receptacle. Fig. 6 is a detail sectional view of the bottle rack.

Similar numerals of reference indicate corresponding parts in all the figures of the drawings.

In the construction illustrated in the accompanying drawings, 5 represents a framework having the front bar, 6, the rear bar, 7, and the end bars, 8, the front and rear bars being connected at intermediate points, at equal distance upon each side of the center, with horizontal supporting-bars 9, and the end bars, 8, being provided with similar supporting bars, 10. Under the center of the framework is arranged a refrigerator or ice-chest of any suitable or approved construction.

11 represents a skeleton frame which is fitted in the supporting frame with its extremities resting upon the supporting bars, 9, and in the center of this frame, 11, is an opening, 12, having beveled edges, and on each side of the opening, 12, is a bottle receptacle consist-

ing of a pendent sheet-metal box, 13, the upper edges of which are bent laterally and secured to the under surface of the skeleton frame around the side openings, 14. Within the bottle receptacle is arranged a series of angular brackets, 15, upon which rests the rack or false cover, 16, provided with a series of bottle openings, 17. Arranged in these bottle openings are closures, comprising a series of radially-disposed, sector-shaped wings or flaps, 18, with their adjacent edges in contact and their apexes separated or cut-away sufficiently to form small perforations, 19, of a size to receive the neck of a bottle. These wings or flaps are formed of flexible, elastic material, such as sheet rubber, and they are preferably formed integral with a thickened ring, 20, which is attached firmly to the under surface of the rack or false cover around the opening in the latter. The flexible wings or flaps yield to the pressure of a bottle and enable the latter to be introduced into the space below the rack, and then resume their normal positions and inclose the neck of the bottle in such a manner as to exclude warm air and retain the low temperature within the receptacle. When a bottle is withdrawn the wings or flaps yield during the passage thereof and then resume their former positions to prevent the raising of the temperature in the space beneath the rack. The rack is held in position within the receptacle, to prevent its displacement during the withdrawal of a bottle, by a stud, 21, arranged at one end superjacent to the bracket, 15, at that end of the receptacle, and a spring catch, 22, arranged in corresponding proximity to the bracket 15 at the opposite end of the receptacle. The bottle receptacles, two of which are illustrated in the drawings, are duplicates of each other and are each provided with a removable cover 23 which may be employed during the time that the bench is not in use, but is unnecessary under ordinary circumstances. Within the central opening, 12, is fitted a drip-pan, 24, having flared flanges, 25, to correspond in inclination to the beveled edges of the opening, whereby a tight joint is formed without requiring that the tray be cemented in place. 26 represents the faucet-box and 27 the

faucets which are arranged above the drip-pan, the latter being provided with an outlet or drain, 28, at the lowest point of its bottom.

29 represents duplicate trays, arranged at opposite ends of the supporting framework, in a double device such as is illustrated in the drawings, with their outer ends resting upon the supporting bars, 10, and their inner ends resting upon the similar bars, 9. A description 10 of one of these trays will be sufficient. The tray fits within the rectangular supporting frame and is provided at its inner end (adjacent to the skeleton frame,) with an opening, 30, beneath which is disposed the rinse-tub, 31, 15 preferably formed of sheet metal and having its upper edges flared laterally and secured to the under-surface of the tray. A portion of the surface of the tray is ribbed to form a draining surface, 32, and adjacent to the rinse-tub is arranged a rest, or mixing surface, 33, 20 upon which to rest glasses, bottles, &c., during the operation of mixing a drink. The upper or outer edge of this rest is rounded or beveled, as shown, to prevent the lodgment 25 of moisture by causing it to flow around the edge and enter the tub. A deflecting block, 34, is arranged at the rear edge of the tray to direct the drippings into the tub. As above described, the inner or adjacent ends of the tray and the skeleton frame rest upon a supporting bar, 9, and the said adjacent ends are rabbeted, respectively upon their upper and lower sides, to interlock and thus form a water tight joint, as shown at 35.

30 The trays and the skeleton frame are provided at their outer edges with vertical flanges, 36, to prevent moisture from reaching the under surfaces of the parts.

35 The upper or exposed surfaces of the trays, 40 skeleton frame, &c., are enameled upon a base

of rolled sheet or plate metal, as being free from oxidation and corrosion and more readily kept clean.

Changes in the form, proportion and minor details of construction may be resorted to 45 without departing from the spirit or sacrificing any of the advantages of my invention.

Having thus described my invention, what I claim, and desire to secure by Letters Patent of the United States, is—

1. In a device of the class described, the combination with a bottle receptacle, of a rack 55 removably fitted therein and provided with temporary fastening devices, said rack being provided with bottle openings, and flexible closures arranged in said openings and divided radially to form sector-shaped wings, the apexes of which are cut away to provide central spaces for the necks of the bottles, substantially as specified.

2. A work-bench for saloons comprising a supporting framework provided with spaced transverse supporting bars, a skeleton frame 65 fitted within the supporting framework and carrying a drip-pan, a bottle receptacle fixed to said skeleton frame, a tray removably fitted within the framework, inclined downwardly toward its inner end and provided at its lowermost end with a rinsing tank, and a flat raised surface, 70 arranged adjacent to said tank, all constructed and arranged substantially as specified.

In testimony that I claim the foregoing as my own I have hereto affixed my signature in the presence of two witnesses.

CHARLES E. GROVES.
